United States Patent

Des. 235,220
Patented May 27, 1975

235,220

GUITAR HEAD

Hari Matsuda, Evanston, Ill., assignor to G. Leblanc Corporation, Kenosha, Wis.

Filed June 18, 1973, Ser. No. 370,772

Term of patent 14 years

Int. Cl. D17—03

U.S. Cl. D56—1 A

FIG. 1

FIG. 2

FIG. 3

FIG. 4

FIG. 1 is a front elevational view of a guitar head showing my new design;

FIG. 2 is a left side elevational view, the right side being a mirror image thereof;

FIG. 3 is a top plan view; and

FIG. 4 is a rear elevational view.

I claim:

The ornamental design for a guitar head, as shown and described.
